(57) CLAIM

The ornamental design for a container for liquid, as shown and described.

DESCRIPTION

FIG. 1 is a perspective view of a first embodiment of the container, showing the new design;

FIG. 2 is a front view thereof;

FIG. 3 is a rear view thereof;

FIG. 4 is a side view thereof;

FIG. 5 is a top view thereof;

FIG. 6 is a bottom view thereof;

FIG. 7 is a perspective view of a plurality of the containers of FIG. 1 arranged in a package according to a second embodiment of the present invention.

FIG. 8 is a front view thereof;

FIG. 9 is a rear view thereof;

FIG. 10 is a side view thereof;

FIG. 11 is a top view thereof; and,

FIG. 12 is a bottom view thereof.

The broken line showing on the container in FIGS. 1-12 is included for the purpose of illustrating environment and forms no part of the claimed design.
